UNITED STATES PATENT OFFICE.

JACOB W. LATTIG, OF WYNCOTE, AND CHARLES LANE GOODRUM, OF PHILADELPHIA, PENNSYLVANIA, ASSIGNORS, BY MESNE ASSIGNMENTS, TO THE DEAN ELECTRIC COMPANY, OF ELYRIA, OHIO, A CORPORATION OF OHIO.

TELEPHONE TOLL-STATION APPARATUS.

No. 859,775.

Specification of Letters Patent.

Patented July 9, 1907.

Application filed November 3, 1903. Serial No. 179,663.

To all whom it may concern:

Be it known that we, JACOB W. LATTIG and CHARLES LANE GOODRUM, citizens of the United States, residing respectively in Wyncote, Montgomery county, Pennsylvania, and in Philadelphia, Philadelphia county, Pennsylvania, have jointly invented a new and useful Improvement in Telephone Toll-Station Apparatus, of which the following is a specification.

Our invention relates to apparatus installed at a substation in a telephone system, in conjunction with suitable transmitting and receiving instruments, whereby a call may be extended to the central office for connection with some other station, any required toll being paid and the operator at central advised of the payment thereof in advance of conversation, and the amount returned to the caller if the desired connection cannot be obtained.

The object of our invention is the production of a compact form of mechanism to perform the stated functions with maximum efficiency and certainty, and with the least possible complication in working parts.

We attain our objects by combining our special mechanism with the ordinary switch of the telephone in such manner that the following operations are performed: the receiver is first taken down and a call extended to central; the number wanted is stated and the proper amount of toll is deposited, either in coins or suitable tokens; if the desired connection is obtainable the caller acting in conjunction with the central office operator deposits the coins in their final receptacle and the operator is automatically signaled. The conversation then proceeds as usual. If the desired connection cannot be obtained the caller is so informed, and upon hanging up his receiver the toll is automatically returned to him without requiring any further special act either on his part or on that of the operator.

The essential parts of our apparatus include a retaining device to receive the coins or tokens when first inserted, this device normally holding them in a neutral position for final disposition, and being connected with the switch-hook so that if the receiver is hung up without further change, the coins will be thrown out through a suitable duct to a point within reach of the caller. The coins being in neutral position, a special signal device is operable by the caller to remove the coins into their final receptacle, and at the same time to signal central of the deposit; but this special device is normally locked, and can be unlocked only by an electro-magnet suitably energized from the central office. The complete toll mechanism may therefore be divided into three principal portions, viz., the

neutral retaining device, the special signal device, and the magnetically controlled lock. 55

Our invention is fully illustrated in the accompanying drawings, wherein the same letters of reference point out the same parts in all the figures.

In these drawings, Figure 1 is a perspective view of a complete telephone instrument, having our invention applied thereto. Fig. 2 is a face view of the lower part of said instrument, with the front of the casing removed to show the apparatus within. Fig. 3 is a vertical section taken on the line $t-x$ of Fig. 2, and looking in the direction of the arrow shown in said figure. Fig. 4 is a top plan view of the parts shown in Fig. 2, the lid or desk of the casing being removed. Fig. 5 is a diagram of the circuits.

Referring to the drawings, Fig. 1 shows a complete telephone wall set having our invention applied thereto. We have chosen this type of set for illustration for convenience, but it will be understood that the invention is not limited thereto. All special parts are inclosed within a box or casing, which in a desk set would of course be separate from the desk standard, 75 in the same way that the magneto bell outfit is now made separate. In this wall set, B is the back-board, upon which is mounted at the upper end a box inclosing the ringer and bearing upon its front the gongs, of usual pattern. Upon this box are mounted the line, "mate" and ground posts, while below it is secured the transmitter arm carrying the transmitter, T. To the left of this arm are the binding-posts, t , for the receiver, which is not shown, as it forms no part of our invention, and its omission simplifies the drawing. 85

Upon the lower part of the back-board is mounted the toll-box, B' , corresponding to the battery-box of magneto phones. In the present instance, however, we have illustrated an instrument without any magneto attachment, current for calling as well as for talking being derived from the central office over the line-wires. The box, B' , has the usual desk top, b , and is fitted with a paneled front, b' , secured in place as shown, having below it the coin drawer or receptacle proper, B^3 , and above it a transverse bar, b^2 , to 95 which reference will be made later. A switch-hook, H, protrudes from the left-hand side of the box, B' , the upper or open end of its escutcheon being closed by the desk lid, b . The latter, as well as the till or coin receptacle, B^3 , is secured by a suitable lock 100 shown in the drawing as an ordinary telephone lock, but in practice of proper design to resist tampering.

In the desk lid is fitted an escutcheon, d , having coin slots, d' , opening into coin chutes, to which reference will be made later. An escutcheon is also 105 fitted to the front bar b^2 , and through it project

of plungers, P and P', provided with push-button heads p and p'. The front panel, b', is pierced at its lower end, the opening being provided with a lip or pan, d²⁰.

Having thus described the external appearance of the instrument, it will be possible to refer to its functions as they would appear from a casual inspection. A person desiring to use the telephone removes the receiver (not shown) from the hook, H, permitting the latter to rise and close the line-circuit, thereby signaling central in the usual manner. If the amount of toll is known it may be deposited at once in the proper opening d', but if not the operator names the amount upon receiving the number wanted. If the desired connection is obtainable, the operator then instructs the user to push his button or buttons, as the case may require. He does so, with the result that a gong or gongs within the box, B', will produce a loud and resonant vibration, which being communicated through the back-board and transmitter-arm to the transmitter, may be heard by the operator at central. Thus apprised of the deposit of the correct amount of toll, the operator permits the connection to proceed in the usual manner. If the desired connection cannot be obtained, the operator so announces, and the user performs no further act beyond hanging up the receiver, his disappointment being mitigated thereupon by the prompt reappearance of his coins in the pan d²⁰.

Referring now to Figs. 1, 2, 3 and 4, E is a cross-bar supported between the side B' of the outer casing, and an intermediate partition B¹⁰, offset from the outer side of the casing B⁴. The pocket thus formed between the members B¹⁰ and B⁴ is utilized for the reception of the condenser C ordinarily used in common battery telephone sets. This condenser is inserted from the top, as shown in Fig. 4, and has its terminals c and c' exposed when the desk lid b is taken off. The removal of the desk lid, it will be observed, gives access also to all the working parts of the apparatus.

Mounted upon the upper side of the cross-bar E is a standard upon which is pivoted the long lever h of the receiver-hook H. In proximity to this standard are mounted the contact springs h³, adapted when the hook is up to be forced against the fixed contact strip h², to close the talking circuit. These parts may be of any usual or desired construction, as they form no part of our invention, but are merely ancillary thereto. The switch-hook has a constant upward tendency due to the strong leaf spring h'. Secured at the rear side of the cross-bar E is the coin ejection chute D². As best shown in Figs. 2 and 3, this chute is supported by wings D³ and D⁴, fastened to the side members B' and B¹⁰, respectively. This chute has a large body portion with its extended upper end d⁴ opening below the coin chutes D, D', the body D⁴ being vertically in line therewith. The lower part of this chute D² is reduced in size and is inclined forwardly to meet the opening in the panel b'. Its side walls are inclined to form a contracted spout d³, which is fitted to the opening in the front panel and lies in position to deliver coins upon the pan d².

At the upper end of the chute D² is pivoted the pan or coin-receiver and holder D⁵, having an extended

pin d⁸ at one side which is connected by a link d⁷ to the post d⁶ upon the switch-hook lever h. When the switch-hook is up, therefore, this coin-holder is maintained in a horizontal position as shown in Figs. 3 and 4, but when the hook is down, owing to the receiver being hung thereon, the coin-holder is turned downwardly about its pivots to open a passageway from the upper chutes D, D' straight through into the lower chute D². As long as the telephone receiver is on the hook, therefore, any coins that are deposited will pass directly through and out into the pan d²⁰.

Secured transversely upon the cross-bar E are two plates P² and P⁴, having rear end extensions between which the pan or coin-holder D⁵ is pivoted, and having upturned flanges p⁶—p⁸ and p⁷—p⁹, respectively. The coin chutes D and D' are mounted upon the rear ends of these plates, as well as the pan D⁵, and all the other operating parts are either mounted thereon or carried by the cross-bar E. This answers a double purpose, first, grouping the parts on a common support for adjustment, and second, making them all removable as a unit by the removal of the cross-bar E. The spindle P passes through the flanges p⁶ and p⁸ on the plate P², being provided with an insulating collar s, a retracting spring p² between the collar and the rear flange p⁸, and a head p⁴ lying outside of said flange, against which it is maintained by the tension spring. Similarly, the spindle P' passes through the flanges p⁷ and p⁹ has an insulating collar s, a spring p³, and a head p⁵.

Secured upon the respective flanges p⁷ and p⁶, and extending rearwardly to points beyond the upper coin chutes, are four stiff leaf springs, having their ends bent toward each other in pairs to form cams g²—g⁴ and g⁵—g⁶. The springs are lettered g⁶—g⁸, and g⁷—g⁹. Upon spring g⁷ is secured an extended clapper-rod g, and upon the spring g⁶ is secured an extended clapper-rod g'. The terminal clapper on the first of these rods lies in position to strike a gong G, when the spring g⁷ is snapped, while the terminal clapper on the second rod lies in a position to engage the periphery of gong G' when the spring g⁶ is snapped.

All these parts are so adjusted that when either of the plungers is pushed in, its head p⁴ or p⁵ will pass freely under the corresponding coin-chute D or D', over the coin-holder and between its pair of cams g²—g⁴ or g⁵—g⁶, without producing any effect. The coin-receiver or holder D⁵, with its connections to the switch-hook, constitutes the first of the three elements hereinbefore referred to. The plungers, acting in conjunction with the cams and clapper-rods, when coins have been inserted, form the second element of the invention; and the third element is the magnetically controlled locking device which we will now proceed to describe.

Mounted upon the lower face of the cross-bar E is a yoke-base M³, carrying the electro-magnet M and the intermediate adjustable pillar M². Upon the lower end of this pillar is carried the armature-yoke m⁴, in which is pivoted the armature m. The cores and armature of the electro-magnet are permanently polarized by the bent steel magnet M'. Extending upwardly from the armature is the bent rod m', which first passes up in front of the yoke M³, then back over the same to the rear side of the cross-bar E, then up a little in front of the coin-chutes D—D', finally ter-

minating in a bent-over end m^5 , which lies in a notch in the upper edge of a slide-plate U, having end slots engaging headed pins on the front faces of the coin-chute tubes D and D', upon which it is adapted to reciprocate back and forth. The rod m^1 is normally held to the left by a spring m^2 adjustably secured to a post m^3 on the cross-bar E. This gives the armature m a normal bias to the position shown in the drawing, and maintains the slide-plate U in the position shown in Fig. 2, two projections u and u' , on the plate being thus brought directly in the path of travel of the plunger-heads p^4 and p^5 . (See Figs. 3 and 4).

The slide-plate U constitutes a locking device for the plungers, and it is controlled by the magnet M, but this magnet is normally disconnected from the telephone circuit in order to avoid possible troubles. It is adapted to be connected thereto in the initial movement of either plunger, however, by the following means: Between the plates P² and P³ is secured a block 20 of insulating material S'. Upon one end of this block is secured a U-shaped contact spring with its body transverse to the block and its two arms s^2 and s^3 extending forwardly along and above the plungers, being slightly bent down in a position to be engaged and raised by the collars s when the plungers are pushed in. At the forward end of the block S' is secured a transverse contact s' , whose opposite ends overlie the spring arms s^2 and s^3 , engaging the latter when they are raised by the plungers. As shown in the diagram, in Fig. 5, the contact s' is connected to the magnet M, and the latter to one of the contact springs h^3 . The spring S on the other hand is connected to the ground post. The bent frame h^1 , which constitutes the back contact for the springs h^3 , is connected to one side of line. Thus when the switch-hook H is up and either plunger P or P' is pushed in, the magnet M is temporarily connected from the line to ground and may be affected by current sent from central.

Having thus described the three elements of our invention, it remains to explain in detail the operation of the parts. In all the figures the parts are shown in normal position, about to call. The user takes down the receiver and permits the switch-hook H to rise. Suppose the required amount of toll to be ten cents—he drops a dime in the right-hand slot d' , whence it passes into the chute D' and down therethrough until it strikes the receiving pan or holder D⁵, which being up retains the coin on edge. It cannot fall forwardly for reason of the lower edge of the chute, and it cannot fall rearwardly by reason of the cam faces. The coin is thus held in a neutral position, from which it may either be deposited or recovered. Supposing the connection can be obtained, the operator tells the user to push his button, whereupon he pushes in the right-hand plunger P'. The first effect of this is that the collar s raises the spring arm s^3 , (see Fig. 4.) into contact with the part s' , which connects the magnet M to line. The operator at central, as indicated in the diagram, is enabled to reverse the direction of current-flow on the line at will, and for a successful call she reverses it from normal. The magnet thereupon throws over its armature, moves the rod m^1 to the right, and thereby carries the slide-plate U with its projections out of the path of the plungers. All this happens while the

plunger P' is moving in. The slide-plate being out of the way, it continues to move in until the head b^5 engages the coin that is standing on edge, and forces it back between the cams g^2 and g^4 , which are thereby forced apart, the spring g^6 in particular yielding to permit the passage of the coin. This carries back the 70 clapper-rod g^7 , and when finally the coin snaps out from between the cams, the spring g^6 recovers suddenly, and the clapper on the rod g^7 is brought sharply into engagement with the gong G'. Each of the gongs has a distinctive tone, and when the operator hears the 75 sound of gong G', she knows that a dime has been deposited. The coin after snapping out from between the cams is pushed over the edge of the holder D⁵ and drops into the receptacle B³ in the bottom of the casing. If desired, a third guide-way or chute may receive the 80 coins thus deposited, and its lower end may be inserted through an opening in the closed lid for the till or coin receptacle B³, thus preventing access to the coins by repair men and others.

The above operation enables the user to proceed with 85 his conversation if the connection can be obtained. If it cannot be obtained, however, the plunger-head p^5 goes against the slide-plate projection u' , and goes no farther, supposing the button to be pressed through mistake. As a matter of fact, when the operator says 90 "line busy" the user of the telephone need perform no further act except to hang up his receiver. As soon as he does this the lever h is moved downwardly, and through the link d turns down the pan D⁵, permitting the coins previously deposited to fall into the open 95 mouth d^4 of the chute D², whence they pass out to the user at d^2 , as previously described.

We have thus carefully and specifically set forth a complete embodiment of the three elements of our invention, viz., the coin-receiving and holding device 100 D⁵, the special signaling and depositing device comprising the plungers, the cams and the gongs, and the locking device, comprising the switch, the magnet and the slide plate. We are fully aware, however, that many changes might be made in this apparatus without 105 departing from the spirit of our invention or from the combination of the three elements described. We wish it understood, therefore, that all such changes and departures are contemplated by us, and we consider them within the scope and purview of the claims, 110 whose language is intended to cover our invention broadly.

Having thus described our invention, what we claim and desire to secure by Letters Patent of the United States is:

115

1. In a telephone toll-station apparatus, the combination of the following instrumentalities: a coin receiver or holder normally in a neutral position, means controlled by the subscriber to deposit a coin thereon and thereafter to pass the coin from the holder into a receptacle and thereby to transmit a special indicating signal, locking means controlled over the line from the central office to automatically control such passage and signal transmission, together with means controlled by the subscriber in such case to recover his coin, substantially as described.

120

2. In a telephone toll-station apparatus, the combination of the following instrumentalities: a switch hook and contacts controlled thereby, a coin chute, a coin receiver or holder in proximity to the coin chute, a plunger adapted to reciprocate across the receiver to remove a coin therefrom, a signal lever moved by the coin in its travel, a

125

130

- locking slide normally in the path of said plunger, an electro-magnet automatically controlling the position of said locking slide, and a connection from the switch-hook lever to the coin receiver, together with circuit connections, whereby said magnet may be controlled from the central office or other distant point, substantially as described. 5
3. In a telephone toll-station apparatus the combination of the following instrumentalities: a coin chute, a coin receiver or holder beneath the chute, a closed receptacle and an opening therefor to one side of the coin receiver, a coin discharge opening, a chute beneath the coin receiver, a reciprocating plunger adapted to be moved across the face of the coin receiver to detach a coin from the same and project it into the receptacle, a switch-hook lever and a connection therefrom to the coin receiver or holder, a lock for the reciprocating lever, an electro-magnet automatically controlling said lock, circuit connections for said magnet and a switch operated in the movement of the plunger to close said circuit connections, substantially as described. 10
4. In a telephone toll-station apparatus, a closed box or casing a coin opening in the top thereof and a coin retaining receptacle within the lower part thereof, together with an intermediate mechanism contained within the box and comprising the following instrumentalities: a pivoted coin receiver or holder beneath the coin opening, a switch-hook lever and a connection therefrom to the coin receiver to move the latter when the switch-hook is moved, a coin discharge chute having its upper end beneath said coin receiver and its lower end opening without the box or casing, a normally retracted plunger having its outer end provided with a push-button on the outside of the box, and its inner end in proximity to the coin receiver, a signal lever and an abutment having an opening between them greater than the diameter of the plunger, but less than the diameter of a coin, and lying in the path of the plunger, a slide normally in the path of the plunger and at such a distance therefrom as to permit its limited movement but to prevent its reaching the coin or effecting a signal, an armature and lever connected with said slide and adapted when moved to remove the slide from the path of the plunger, an electro-magnet controlling said armature and means to permanently polarize the same, line connections for said magnet, and a normally open switch therein adapted to be closed in the first movement of the plunger, substantially as described. 15
5. In a telephone toll-station apparatus, a coin chute, a coin receiver or holder, a manually operable plunger adapted to be moved across the coin receiver and to detach a coin therefrom, a stop to limit the movement of said plunger, an electro-magnet to automatically control said stop and a circuit for said magnet closed in the initial movement of the plunger, substantially as described. 20
6. In a telephone toll-station apparatus, a special signal device having a movable operating part, a lock for said movable part, an electro-magnet automatically controlling said lock, and circuit connections for said magnet closed in the initial movement of the movable part, whereby the signal may be retained or exhibited according to the condition of said circuit, substantially as described. 25
7. In a telephone toll-station apparatus, a coin receiver and a coin depositor or projector, a magnetic detent for said depositor automatically controlling the deposit there- 30
- by, and a circuit therefor closed in the initial movement of the depositor, substantially as described. 65
8. In a telephone toll-station apparatus, a coin chute, a pivoted coin receiver or holder beneath the same, a switch-hook lever and a connection therefrom to maintain the coin receiver raised when the instrument is in use, an inner coin receptacle adapted to receive coins projected from the side of the coin receiver, and an ejection opening beneath the coin receiver, together with manually operable means to project the coin from the receiver into the receptacle, substantially as described. 70
9. In a telephone toll-station apparatus, an inlet opening or chute, a pivoted coin receiver or holder beneath said chute, a switch-hook connected to move said coin receiver in its operation, a gong and a striker therefor having a cam face, a reciprocating plunger, a detent therefor and a magnet automatically controlling the same, together 75
- with means whereby said plunger will close the circuit of the magnet in its initial movement, thereafter if not detained will engage a coin on the coin receiver, and will finally with the coin engage the cam to strike the gong, depositing the coin thereby, substantially as described. 80
10. In a telephone toll-station apparatus, a coin receiver or holder, a signal sounding or transmitting device, an operating lever therefor extending across the coin receiver and provided with a cam face, a spring abutment also extending across the coin receiver and having a cam face 90
- symmetrically and oppositely arranged to the first, a plunger constructed and arranged so that when no coin has been deposited it will pass between the cam faces without engaging the same, or if a coin has been deposited it will engage the coin, force the same into engagement with the opposite cam faces, thereby moving the operating lever, and sound or transmit a signal, together with a locking device for said plunger controlled from the central office substantially as described. 95
11. In a telephone toll-station apparatus, a coin chute, a coin receiver or holder, and two openings for the passage of coins therefrom, a plunger manually operable to move across said coin receiver and project a coin into one opening, together with means automatically controlled by the switch-hook lever of the telephone-set to move the coin 100 receiver and project the coin thereby into the other opening, substantially as described. 105
12. In a telephone toll-station apparatus, a coin chute, a receiver or holder, and two openings for the passage of coins therefrom, a plunger manually operable to move across said coin receiver and project a coin into one opening, and means automatically controlled by the switch-hook lever of the telephone-set to move the coin receiver and project the coin thereby into the other opening, together with a detent in the path of said plunger, a magnet 110
- automatically controlling the same, and a circuit therefor closed by the plunger in its initial movement, substantially as described. 115

In witness whereof, we have hereunto signed our names in the presence of two subscribing witnesses.

JACOB W. LATTIG.
